METHOD AND APPARATUS FOR TREATING
YARN WITH LIQUIDFrederick Farwell Long, Chester, Pa., assignor to
The Viscose Company, Marcus Hook, Pa., a
corporation of PennsylvaniaApplication August 24, 1933, Serial No. 686,591
Renewed May 4, 1935

12 Claims. (Cl. 8—19)

This invention relates to method and apparatus for treating yarn with liquid, and more particularly to processes and machines of this character for washing, bleaching or dyeing yarn.

5 The main objects of the invention are to facilitate and improve the operations of washing, bleaching, dyeing and the like, to prevent interference therewith of air bubbles, to avoid disarranging of the yarn, and to improve the construction of apparatus for this purpose.

In the accompanying drawing—

Figure 1 is a vertical section through apparatus for carrying out the process, both according to the preferred embodiment of the present invention,

15 Figure 2 is a detail elevation of a part of the structure shown in Figure 1, and

Figures 3 and 4 are modifications of Figure 2.

The present invention is adapted for use with 20 an ordinary bleaching machine, such as described in Patent No. 1,116,242 issued November 3rd, 1914 to James Clayton, the drip tank 31 of which is shown, stationarily supported above the framework of the machine by brackets 4, and perforated to cause a rain or series of small streams of 25 treating liquid to drip therefrom.

According to the present invention, a crate or carrier 5 is provided, being supported by trunnions 6 secured to the sides of the carrier. These 30 trunnions take the place of the ordinary bleach rod in the old machine hereinbefore referred to. These trunnions 6 rest in sockets 7, which are moved along by the machine, causing the carrier 6 to pass horizontally under the drip pan 31.

35 The yarn is supported in the carrier on rods 8 which extend horizontally therein, but are arranged to support the yarn in inclined position, each rod being higher than the next outer rod. The carrier 5 is substantially water tight, but is 40 provided with a drain valve 10 at or near the bottom thereof.

A lever 11 has one end connected to the valve 10, and the other end forming a follower 9 co-acting with a cam 12 mounted on the stationary frame of the machine. A spring 13 normally holds the valve 10 closed.

In operation the skeins of yarn 14 are preferably wrapped in open mesh cloth, such as cheese cloth or tobacco cloth, and placed in the carrier 5, being supported by the rods 8 in the inclined position shown. The machine then moves the carrier horizontally, under the streams of treating liquid dripping from the pan 31. The liquid passes through the skeins, and as the rods 8 sup-

port the same only at intervals, the liquid passes on down between the rods.

The spring 13 holds the valve 10 closed, so that the treating liquid is trapped in the carrier 5, and the level thereof rises as the carrier moves forward, gradually immersing the skeins. Then the follower 9 engages the cam 12 causing the lever 11 to open the valve 10. This permits the trapped pool of treating liquid to drain out of the carrier 5.

10 When the follower 9 rides off the cam 12, the spring 13 closes the valve 10, and the carrier 5 again begins to fill with treating liquid trapped therein from the streams dripping from the tank 31. It will be understood that there are a number of cams 12 spaced along the path of the carrier 5, and the tank 31 extends therealong so that the filling and draining of the carrier is continued alternately along the horizontal path thereof through the machine.

15 Because the bundles of yarn 14 are tilted at an angle, any air within the bundles is lifted by the liquid to one end of the bundles where it will not prevent proper penetration of the liquid. Also the immersion tends to dislodge the air, and 20 the alternate dripping and immersing of the inclined bundles further tends to the elimination of air bubbles.

25 As contrasted to the former methods, the present invention results in the diamonds in the skeins remaining more clearly defined, the lacings are not washed around the skeins, the bagginess of the skeins is eliminated, and the twist of the yarn is better preserved as it is not washed to one end of the skein. Furthermore, broken 30 filaments if present are not washed into adjacent threads to cause matted condition, and the skeins are protected by the wrapping thereof, from mechanical damage by impact of the treating liquid.

35 It is obvious that alternate methods may be used to discharge rapidly the liquor from the carrier after this liquor has attained a pre-determined height. For example, a siphon arrangement 20 as shown in Fig. 3 may be used, or 40 a valve operated by a float control 22 as shown in Fig. 4. Thus various means may be used to bring about a fundamental idea of the invention, namely, the repeated immersion of the 45 yarn in the treating liquor with alternate draining therefrom.

I claim:

50 1. Method of treating yarn with liquid, which comprises dripping treating liquid on the yarn, collecting a bath of said treating liquid, main- 55

- taining said yarn oblique to the surface of said bath, raising the surface of said bath to immerse said yarn therein and thereafter draining said bath, and alternately repeating said immersion and draining steps while continuing said dripping. 5
2. Method of treating yarn with liquid, which comprises causing treating liquid to drip on the yarn, collecting a bath of said treating liquid, 10 maintaining said yarn at a constant acute angle to the free surface of said bath, raising the level of said free surface to immerse said yarn therein and thereafter draining said bath, and alternately repeating said immersion and draining steps 15 while continuing said dripping.
3. Method of treating yarn with liquid, which comprises dripping treating liquid on the yarn, collecting a bath of treating liquid, maintaining said yarn at an acute angle to the free surface 20 of said bath, raising said surface to pass the treating liquid upward through and immerse said yarn, draining said bath, and alternately repeating said draining and immersion steps while continuing said dripping. 25
4. Method of treating yarn with liquid, which comprises dripping treating liquid on the yarn, collecting a bath of treating liquid, maintaining said yarn at an acute angle to the free surface of said bath, raising said surface to cause said bath 30 to pass the treating liquid upward and immerse said yarn, draining said bath, and alternately repeating said draining and immersion steps while moving said bath and said supported yarn horizontally as a unit and while continuing said dripping. 35
5. Method of treating skeins with liquid, which comprises wrapping said skeins with open mesh cloth, dripping treating liquid on said wrapped skeins, collecting a bath of said treating liquid, maintaining said wrapped skeins oblique to the 40 surface of said bath, raising the surface of said bath to immerse said wrapped skeins therein and thereafter draining said bath, and alternately repeating said immersion and draining steps 45 while continuing said dripping.
6. Apparatus for treating yarn with liquid, which comprises means for dripping treating liquid on the yarn, means for collecting a bath of said treating liquid, means for maintaining said yarn oblique to the surface of said bath, means 50 for raising the surface of said bath to immerse said yarn therein and thereafter draining said bath, and means for alternately repeating of said immersion and draining steps while continuing said dripping. 55
7. Apparatus for treating yarn with liquid, which comprises means for causing treating liquid to drip on the yarn, means for collecting a bath of said treating liquid, means for maintaining said yarn at a constant acute angle to the 60 free surface of said bath, means for raising the level of said free surface to immerse said yarn therein and thereafter draining said bath, and means for alternately repeating said immersion and draining steps while continuing said dripping. 65
8. Apparatus for treating yarn with liquid, which comprises means for causing treating liquid to drip on the yarn, means for collecting a bath of treating liquid, means for supporting said yarn at spaced intervals to maintain said yarn 70 at an acute angle to the free surface of said bath, the area between said supported intervals being sufficient to permit the treating liquid to pass vertically through the yarn, means for raising the level of said free surface to cause said bath to 75 pass upward between said supported intervals and immerse said yarn, means for draining said bath, and means for alternately repeating said draining and immersion steps while continuing said dripping. 5
9. Apparatus for treating yarn with liquid, which comprises means for causing treating liquid to drip on the yarn, means for collecting a bath of treating liquid, means for supporting said yarn at spaced intervals to maintain said yarn at an acute angle to the free surface of said bath, means for raising the level of said free surface to cause said bath to pass upward between said supported intervals and immerse said yarn, means for draining said bath, means for alternately repeating said draining and immersion steps, and means for moving said bath and said supported yarn horizontally as a unit while continuing said dripping. 10
10. Apparatus for treating yarn with liquid, which comprises a frame, an elongated drip tank supported thereon, a carrier tank, means in said tank for supporting skeins of yarn therein at an acute angle to the horizontal, means for passing said carrier tank with the skeins supported therein along said frame under said drip tank, a valve in said tank, means spaced along said frame within the extent of said elongated drip tank for periodically opening said valve, and means for periodically closing said valve between said opening intervals. 20
11. Method of treating skeins of yarn comprising twisted filaments wound with a traverse forming diamonds, which comprises wrapping the skeins with open mesh fabric, supporting the wrapped skeins, moving said supported skeins along a horizontal path, causing treating liquid to drip on the wrapped and supported skeins from points closely spaced and substantially uniformly distributed along said path as a rain and pass through said fabric cover and the skein therein, whereby the skein is protected by said cover from mechanical damage by impact of said rain of treating liquid, and the diamonds in the skein and the twist of the yarn are protected from disarrangement by the flow of treating liquid, and causing a pool of treating liquid supported and moving with said skein to accumulate from said rain and the level thereof to rise within said cover and immerse at least a portion of the skein therein. 30
12. Method of treating skeins of yarn comprising twisted filaments wound with a traverse forming diamonds, which comprises first wrapping said skein so formed and wound in a cover of open mesh fabric permitting passage of treating liquid but of sufficiently close mesh to protect said filaments, supporting said wrapped skein, moving said supported and wrapped skein in a horizontal path, dripping treating liquid as a rain on said wrapped and supported horizontally moving skein from points closely spaced and substantially uniformly distributed along said path, whereby said liquid passes through said cover and the skein therein but said filaments are protected from mechanical damage due to impact of said rain and said diamonds in the skein and the twist of the yarn are protected from disarrangement by the flow of treating liquid, accumulating a pool of treating liquid from said rain while moving said pool horizontally with said skein, and raising the level of said pool and thereby immersing at least a part of said skein in said cover while the skein is moving horizontally and being subjected to said rain. 40
